(57) **CLAIM**

I claim, the ornamental connector keying arrangement, as
shown and described.

DESCRIPTION

FIG. 1 is a front elevation view of a connector keying arrangement showing my new design;

FIG. 2 is a top plan view thereof;

FIG. 3 is a left side elevation view thereof;

FIG. 4 is a rear elevation view thereof;

FIG. 5 is a right side elevation view thereof;

FIG. 6 is a bottom plan view thereof;

FIG. 7 is a top, front and right side perspective view thereof;
and,

FIG. 8 is left and right side elevation views thereof, on a larger
scale.

The broken line in the drawing views represents unclaimed
subject matter only, and forms no part of the claimed design.

It is certified that error appears in the above-identified patent and that said Letters Patent is hereby corrected as shown below:

On the Title Page

Item (73) Assignee: currently identifies an Assignee as: Byrne Electrical Specialists, Inc., Rockford, MI (US). In fact, there neither has been, nor is there now, any Assignee of the patent. Accordingly, none should be identified on the patent.

Signed and Sealed this
Fifth Day of August, 2014

Michelle K. Lee
Deputy Director of the United States Patent and Trademark Office
